(57) **CLAIM**

The ornamental design for a measuring butter cutter, as shown and described.

DESCRIPTION

FIG. 1 is a top plan view of the measuring butter cutter; FIG. 2 is a side elevation view of the measuring butter cutter; FIG. 3 is a top perspective view of the measuring butter cutter;

FIG. 4 is a front elevation view of the measuring butter cutter;

FIG. 5 is a rear elevation view of the measuring butter cutter; and,

FIG. 6 is a top plan view of the measuring butter cutter with measurement and other markings thereon for the purpose of showing the measuring butter cutter in the environment in which it is used.
